UNITED STATES PATENT OFFICE.

HENRY J. HARRIS, OF YOUNGSTOWN, OHIO.

DEVICE FOR PREVENTING COLLECTION OF GREASE ON ROLLS.

Application filed August 27, 1926. Serial No. 131,930.

This invention relates to a device which is adapted to remove grease from the shoulders of the rolls of a rolling mill, it being objectionable to permit the grease to run down the shoulders of the roll and subsequently engage between the working surfaces of the contacting rolls.

A further object of the invention is to provide a device of this character which is simple and inexpensive to manufacture and which may be attached to rolling mills at present employed without the necessity of alteration.

It is necessary to lubricate the journals of the rolls of rolling mills in order to afford easy working conditions but it has been found that due to the heat of the rolls the grease or oil runs from the upper bearings down along the shoulders of the upper roll and subsequently onto the working surfaces of the rolls at their contacting points. This condition causes defective plates and it is to eliminate this condition that the present device has been designed.

With the above objects indicated and other objects hereinafter explained in view, my invention consists in the construction and combination of elements hereinafter described and claimed.

Referring to the drawings:

Fig. 1 is a front elevational view of a rolling mill showing the position of the device constituting my invention.

Fig. 2 is an end elevational view of the mill shown in Fig. 1.

Fig. 3 is a segmentary view taken on line 3-3 of Fig. 2.

Fig. 4 is a cross-sectional view of the device taken on line 4-4 of Fig. 3.

In the drawings, 10 represents the standards of the ordinary rolling mill. The standards 10 have journaled therein upper roll 11 and lower roll 12, the upper roll 11 being provided with neck portions 13 and the lower

roll 12 being provided with neck portions 14. The standards 10 are each provided with a slot 15 and positioned within the slot 15 are upper bearing blocks 16 and lower bearing blocks 17. The bearing blocks 16 are adapted to receive the neck portions 13 of the roll 11 while the bearing blocks 17 are adapted to receive the neck portion 14 of the lower roll 12. A slideable member 18 is positioned within the slot 15 and has upon its inner face a bearing block 19 which engages with the neck portion 13 of the upper roll 11. This slideable mem-

ber 18 is connected to a bolt 20 which is screw threaded into the upper portion of the standard 10 and is adapted to adjust the bearing 19 with respect to the neck portion 13 of the upper roll 11 and thereby regulate the tension of the rolls 11 and 12.

The neck portions 13 of the upper roll 11 are provided with hub extensions 21 while the neck portions 14 of the lower roll 12 are provided with hub portions 22. It is customary to drive one of the lower hub members 22 and the upper roll 11 is rotated by means of its contact with the driven roll 12. The rolling mill so far described constitutes no part of the present invention and is the usual construction employed in connection with rolling mills.

It is customary to keep the bearings well lubricated and in so doing the grease from the upper bearing escapes onto the shoulders of the upper roll 11 and forces its way onto the working or contacting surfaces of the rolls 11 and 12, the presence of which affects the quality of the plates being rolled and which is therefore quite objectionable.

The rotation of the rolls 11 and 12 is comparatively slow and because of this fact the grease from the lower bearings 17 which escapes onto the shoulders of the lower roll 12 does not reach the working surface of the roll which is the case with respect to the upper bearings 16 and the roll 11.

In order to prevent this grease from forcing its way between the contacting surfaces of rolls 11 and 12, I provide a device which is secured to the standards 10 and which has a portion engaging with the shoulders of the upper roll 11 below the neck 13. As the roll 11 rotates the grease which works its way from the bearing 16 onto the shoulders of the roll 11 is scraped off before the rolls 11 and 12 arrive at corresponding contacting points, the grease being permitted to drop upon the lower bearing or may be drawn off in any other suitable manner.

The device comprises a tubular portion 23 made of iron, or any other suitable material, which has a portion 24 bent over at substantially right angles to the tubular portion 23, the portion 24 being provided with an opening 25. This portion 24 is bent at such an angle that it engages the flat end of the standard 10 and extends in a declined manner. A slideable member 26 composed of a piece of strap iron bent into substantially a U-shape, has a leg portion 27 and a leg portion 28, the

leg portion 27 being slidable within the tubular portion 23. The leg portion 28 extends substantially beyond the end of the tubular member 23 and has secured at its end a scraper 29 which is adapted to engage with the shoulder of the upper roll 11. The scraper 29 should be bent at an angle with respect to the upper roll 11 so that the grease which is scraped from the shoulder of roll 11 may be directed downwardly and away from the working surfaces of said rolls.

In order to maintain this scraper 29 in engagement with the shoulders of the roll 11 a spring 30 is provided which has one end secured to the portion 24 of the tubular member 23 and the opposite end secured to the end of the slidable member 26. It will be noted that any irregularity in the shoulders of the roll 11 will have no effect upon the scraper 29 as the scraper will be held in contact therewith due to the tension of the spring 30.

In applying the device to the mill it is only necessary to drill and tap a hole 31 in the end of the standard 10 and to secure the scraping device thereto by means of a bolt 32 passing through the opening 25 in the portion 24 of the tubular member 23. The device, as shown in Fig. 1, is adapted to extend within the slot 15 of the standard 10.

While I have shown and described the device attached in a certain manner and location, it is to be understood that various changes may be resorted to without departing from the spirit of the invention as set forth in the appended claims.

Having thus described my invention, I claim:

1. A device for preventing grease from contacting with the working surfaces of rolls of rolling mills comprising means adapted to be secured to the mill and extending into engagement with the shoulder of a roll.

2. A device for preventing grease from contacting with the working surfaces of rolls of rolling mills comprising a resilient means adapted to be secured to the mill and extend-

ing into engagement with the shoulder of a roll.

3. A device for preventing grease from contacting with the working surfaces of rolls of rolling mills comprising a member adapted to be secured to a part of the mill, a second member slidably engaging the first member and provided with an extension adapted to engage the shoulder of a roll, and means for causing engagement between the last mentioned member and said roll.

4. A device for preventing grease from contacting with the working surfaces of rolls of rolling mills comprising a member adapted to be secured to a mill, a second member slidably within the first member, said second member being provided at its end with means for engagement with the shoulder of a roll, and resilient means at the opposite end to cause engagement therebetween.

5. A device for removing grease from rolls of rolling mills comprising a member adapted to be secured to the mill adjacent the end of the rolls, said member being provided with a longitudinally extending slot, a second member slidably mounted in said slot and having an end extending to substantially the end of the roll, a scraping means secured to the extending end and adapted for engagement with the end of the roll, and a spring having one end secured to the first mentioned member and the opposite end secured to the slidably member, said spring adapted to cause engagement between the scraping means and the end of the roll.

6. In a rolling mill, the combination with a pair of standards and rolls journaled therein, of a means secured to said standard and extending into engagement with the shoulder of said roll to remove grease therefrom and thereby prevent said grease from reaching the working surface of said rolls.

In testimony whereof, I hereunto affix my signature.

HENRY J. HARRIS.
